UNITED STATES PATENT OFFICE

2,568,470

PROGRESSIVE ARC QUENCHER

Charles H. Titus, Philadelphia, Pa., assignor to
General Electric Company, a corporation of
New York

Application December 29, 1949, Serial No. 135,696

1 Claim. (Cl. 200—144)

1

The invention relates to arc quenchers, particularly arc quenchers for operation in connection with the arcing contacts of heavy-duty circuit interrupters.

The principal object is to provide an improved progressive type of heavy-duty arc quencher having relatively movable slotted and landed arc-quenching members one of which is operable with a circuit-interrupting arcing contact for drawing the arc progressively through restricted and enlarged spaces between the members so that the ionized gases sustaining the arc are progressively brought into intimate contact with the lands of the arc-quenching members in the restricted spaces and expanded in the enlarged slotted spaces and thereby rapidly become reduced in temperature and thus de-ionized to extinguish the arc.

A further object is to enable a movable arcing contact mechanically to carry the arc along a narrow extended path between closely adjacent arc-quenching members of insulating material that are relatively movable and provided with opposing series of progressively registering slots and lands for, in effect, grinding and quenching the arc therebetween to induce turbulence and pressure drop in the arc-sustaining gases and thereby expedite the arc-quenching action.

Another object is to provide an improved rotary type of arc quencher structure having a rotatable arcing contact and progressively registering concentric series of relatively rotatable slots and lands for rolling and quenching the arc gases therebetween within a relatively small quadrantal space.

Further objects and advantages of the invention will appear in the following description of the accompanying drawings wherein Fig. 1 is a side view of a heavy-duty circuit interrupter provided with a rotatably mounted arcing contact combined with an improved rotary arc quencher embodying the improvements of the present invention with the circuit interrupter shown in the closed position; Fig. 2 is a similar view showing the relative position of the parts when the circuit interrupter is opened and the arc quenched; Fig. 3 is a partial sectional view along the dash line 3—3 of Fig. 1 showing the details of construction of the relatively rotatable arc-quenching members; Fig. 4 is a side view of a modified form of circuit interrupter provided with an arcing contact movable in a linear path and combined with an arc quencher having progressively registering linear series of slots and lands for quenching the arc therebetween in accordance with the present invention.

As shown in Fig. 1, the heavy-duty circuit interrupter indicated generally by the reference character 10 is of the improved rotary arcing contact take-up type more fully described and

2

claimed in the copending application, Serial No. 135,796, filed December 29, 1949, by John A. Favre, and assigned to the assignee of the present invention. The circuit interrupter 10 is provided with a pair of main current-carrying contacts 11 and 12 that are connected respectively to the terminals 13 and 14 and also respectively to a pair of spaced-apart stationary arcing contacts 15 that are aligned one behind the other as shown in Fig. 1. One of the spaced-apart stationary arcing contacts 15 is connected through conductors 16 and 17 with the terminal 13 while the other contact 15 is connected through conductors 20 and 21 with the terminal 14.

15 As more fully described and claimed in the Favre application, the rotatably mounted bridging contact 22 for engaging and disengaging the pair of spaced-apart stationary arcing contacts 15 is carried on a contact wear take-up arm 23 that is pivotally mounted on pin 24 which in turn is carried on the rotatable base plate 25. The base plate 25 is pivotally mounted on the stationary pin 26 by means of the yoke 27.

20 An improved sequential contact-operating mechanism, also more fully described and claimed in the Favre application, and indicated generally by the reference character 30 is provided with a main operating push-pull rod 31 that is guided in a linear path between the concave rollers 32 and 33 and has a link 34 pivoted on pin 35 carrying roller 36 and guided by the roller mounting pin 37 engaging with the slot 38 formed in the stationary guide member 39 for moving roller 36 into engagement with movable main contact 12 to force contact 12 into wiping circuit-closing engagement with the cooperating main contact 11 against the strain of their respective biasing springs 43 and 44. The hooked member 45 is secured to contact 12 for engagement by pin 37 to enforce the opening of the main contact 12 when rod 31 is moved in the opposite direction.

25 The main operating rod 31 also carries a link 46 pivoted at one end on pin 47 with the other end connected to the knee of the toggle links 48 and 49 that are pivoted respectively on the stationary pin 50 and the pin 51 carried by the pivotally mounted arm 23 so as to sequentially rotate the bridging contact 22 out of engagement with the pair of spaced-apart stationary arcing contacts 15 after the separation of the main contacts 11 and 12 is completed. The disengagement of the rotatable bridging contact 22 effects the final interruption of the circuit and draws arcs between the bridging contact 22 and the spaced-apart stationary arcing contacts 15.

30 In accordance with the present invention, the arcs are quickly extinguished by the improved rotary type of progressive arc quencher shown in Figs. 1 and 2 having relatively rotatable comple-

mentary nested and concentric cylindrical arc-quenching members 55 and 56 formed of suitable insulating materials such as molded phospho-asbestos to provide the several series of slots 57, 58, 59 and 60 and a corresponding series of lands 61, 62, 63 and 64 for quenching the arcs therebetween. As shown in Fig. 1, the series of slots 57 and lands 61 and the opposing series of slots 59 and lands 63 are located in adjacent opposing concentric alignment on one side thereof when the bridging contact 22 is in engagement with the two spaced-apart stationary arcing contacts 15 with the circuit breaker 10 in its closed position. The series of slots 58 and lands 62 likewise are located in opposing concentric alignment on the other side of the bridging contact 22 and the arcing contacts 15 so as to effect progressive registration of the lands in each series with the slots and lands of the opposite series upon opening of the circuit breaker in order to quench the arc therebetween.

The stationary arc-quenching member 55 may be formed of an assemblage of a concave arcuate insulating block 70 provided with the series of slots 57 and lands 61, and a concave arcuate insulating block 71 provided with the series of slots 58 and the lands 62. The blocks 70 and 71 have suitable slots or openings for embedding the spaced-apart arcing contacts 15 therebetween with the face of the arcing contacts in substantial alignment with the convex concentric cylindrical series of lands 61 and 62 of the blocks as indicated in Fig. 3. The blocks 70 and 71 are respectively further provided with deep central arcuate grooves 72 and 73 extending in alignment midway between the spaced-apart arcing contacts 15 as shown more clearly in the partial sectional view of Fig. 3.

The rotatably mounted complementary nesting convex arcing member 56 is of substantially semicylindrical form with suitable provision made for embedding the bridging contact 22 within a recess or tunnel 75 formed therein for receiving the U-shaped bridging member 22 therein while permitting free substantially radial movement of the bridging contact 22 when the arm 23 on which the bridging member 22 is mounted is rotated about the pin 24. The rotating arc-quenching member 56 is suitably secured to the mounting plate 25 so as to rotate about the pin 26 as an axis and thereby maintain relatively close running clearance between the series of lands 63 and 64 formed thereon and the opposing concentric cylindrical series of lands 61 and 62. The rotatably mounted arc-quenching member 56 is provided with a central arcuate-shaped vane 74 that extends into a freely running fit with the arcuate concentrically aligned grooves 72 and 73 so as to provide a continuously effective insulating barrier between the two spaced-apart arcing contacts 15 during the relative rotary motion of the movable arcing member 56 with respect to the stationary arcing member 55 formed by the two concave blocks 70 and 71.

Operation

Referring to Fig. 1, when the operating rod 31 is lowered by suitable automatic overload current-responsive means, not shown, the main contacts 11 and 12 are separated by operation of the link 34 and roller 37 with the hooked member 45 serving to apply a positive force in addition to the opening bias of springs 43 to effect the separation. The separation of the main contacts 11 and 12 shunts the current through the spaced-apart

5 arcing contacts 15 and the bridging contact 22. Upon the rapid sequential separation of the bridging contact 22 from the spaced-apart arcing contacts 15 by operation of link 46 to buckle the toggle links 48 and 49, arm 23 is rotated about pin 24 to withdraw the bridging contact 22 substantially radially within the recess or tunnel 75. At the same time the mounting plate 25 is rotated about pin 26 to carry the semicylindrical arcing member 56 along with the bridging contact 10 10 22 so as to mechanically draw the arcs formed between the bridging contact 22 and the stationary arcing contacts 15 along a narrow path extending between the closely adjacent nesting 15 cylindrical arc-quenching members 55 and 56. In this way, the opposing series of lands 63 and 64 on the movable arc-quenching member 56 are progressively brought into register with the slots 57 and 58 and lands 61 and 62 to quench the arcs therebetween upon rotary movement of the pivotally mounted arc-quenching member 56 and bridging contact 22. As a result, the ionized gases sustaining the arcs are brought into intimate contact with the lands of the relatively movable 25 arc-quenching members when the lands register and expand in the slots between the lands when the slots register so as to induce turbulence and pressure drop in the arc-sustaining gases and thereby expedite the arc-quenching action to extinguish the arc before the parts reach their relative position shown in Fig. 2.

30 During the quenching of the arc between the progressively registering lands and slots of the relatively movable arc-quenching members 55 and 56, the arcuate barrier 74 that runs in the aligned arcuate slots 72 and 73 serves to effectively separate the arcs drawn at the opposite ends of the U-shaped bridging member 22 so that the hot gases sustaining each arc are forced into intimate turbulent engagement with the relatively movable slots and lands on either side of the control barrier 74 to become rapidly cooled, thereby increase the arc resistance at each restricted section and extinguish each arc in a relatively small quadrantal space. The slots between the lands provide for venting the arc gases laterally therethrough and suitable barrier plates, not shown, may be spaced apart on each side of the relatively movable arc-quenching members 55 and 56 in the path of the vented gases. The rapidly expanding gases are cooled and rapidly deionized in order to increase the dielectric strength of the gas. The increased dielectric strength permits a higher steady state and transient recovery voltage to be interrupted.

55 In the modified form of circuit interrupter, shown in Fig. 4, the push-pull operating rod 80 carries a bridging contact 81 in a linear path for engaging between the relatively stationary contacts 82 and 83. However, the contact 82 is pivotally mounted upon the terminal 84 by means of the conducting pin 85 and is biased into engagement with the bridging contact 81 by spring 86. Likewise, contact 83 is pivotally mounted on the terminal 87 by means of the conducting pin 88 and is biased to engage the bridging contact 81 by the spring 89.

In order to quench the arcs drawn upon separation of the bridging contact 81 from the 70 pair of relatively stationary contacts 82 and 83 in accordance with the present invention, two rows of insulating plates 94 and 95, formed of suitable arc resistant insulating material, are mounted between the front and back plates 96 and 97, also formed of insulating material, in parallel

spaced alignment adjacent the linear path of the bridging contact 81 and in predetermined linear alignment with the respective contacts 82 and 83 to provide alternate series of lands 98 and 99 and slots 100 and 101 on opposite sides of the linear path of bridging contact 81. The bridging contact 81 carries for movement therewith an insulating member 104 having the series of slots 105 and 105a formed on the opposite sides thereof to provide a corresponding series of lands 106 and 107 for progressively registering with the opposing alternate series of lands 98 and 99 and slots 100 and 101 to quench the arcs therebetween in substantially the same way as the progressively registering slots and lands of the rotary type of circuit interrupter previously described. Thus, the ionized gases sustaining the arc drawn between the bridging contact 81 and the cooperating contact 82 prior to interruption of the circuit are progressively brought into intimate contact with the series of lands 98 and 106 causing the arc resistance to rise over the restricted sections upon the progressive registration thereof and are expanded in the enlarged spaces provided upon the progressive registration of the series of slots 100 and 105 and thereby rapidly become reduced in temperature and thus deionized to extinguish the arc. Exactly the same arc-quenching is provided by the progressively registering series of lands 99 and 107 and progressively registering series of slots 101 and 106 to quench the arc drawn between the bridging contact 81 and the cooperating contact 83. The alternate registration of the lands and slots induces turbulence and pressure drop in the arc-sustaining gases and thereby expedites the arc-quenching action by virtue of forcing the arc into a series of restricted, high resistance, short arcs having intervening sections which are rapidly deionized by quickly cooled gases which are then capable of withstanding high recovery voltages of a transient and a steady state nature.

What I claim as new and desire to secure by Letters Patent of the United States is:

In combination, a concave arcuate arc-quenching member provided with a series of alternate slots and lands transverse the concave arcuate face thereof and having an arcuate slot formed circumferentially therein, a pair of axially spaced-apart arcing contacts embedded in the concave member with the ends of the contacts in substantial alignment with the lands on opposite sides of the arcuate slot, a convex arcuate arc-quenching member rotatably mounted in nesting relation with the concave member and provided with a series of alternate slots and lands transverse the convex face thereof and having a bridging contact movable therewith for engagement with the spaced-apart arcing contacts, and means for rotating the convex member to disengage the bridging contact and draw arcs between the bridging contact and spaced-apart arcing contacts and progressively register the slots and lands of the rotatable convex arc-quenching member with the slots and lands of the concave insulating member to quench the arc therebetween, and having an arcuate barrier extending centrally therefrom into the arcuate slot formed in the concave member for separating the arcs.
